UNITED STATES PATENT OFFICE.

ARTHUR KLEINFELDT AND BRUNO F. PRIEMER, OF HOBOKEN, NEW JERSEY; SAID PRIEMER ASSIGNOR TO SAID KLEINFELDT.

SIPHON FOR DISPENSING LIQUIDS.

1,099,925.

Specification of Letters Patent. Patented June 16, 1914.

Application filed May 28, 1913. Serial No. 770,813.

To all whom it may concern:

Be it known that we, ARTHUR KLEINFELDT and BRUNO F. PRIEMER, citizens of the United States, and residing in Hoboken, in the State of New Jersey, have invented certain new and useful Improvements in Siphons for Dispensing Liquids, of which the following is a specification, reference being had to the accompanying drawing, forming 10 a part hereof.

This invention relates to siphons for dispensing liquids and has for its principal object to improve the construction of the valves for controlling the discharge of the liquid and the flow of gas from the gas container to the liquid receptacle. In previous constructions the draw-off tap or liquid discharge faucet proper has never been formed as a separate unitary structure from the remaining parts of the siphon and gas container and yet have formed therein the gas valve by which the flow of gas into the liquid receptacle is controlled, although in some constructions it has been proposed to 15 interconnect the two valves operatively so that a single operating lever serves to control the position of each of the valves.

In accordance with this invention the seats of the two valves and the necessary 30 ducts leading respectively from the gas container and the liquid receptacle to the valves, are formed in a single casting. By this arrangement the valves may be assembled in the faucet with the operating lever there- 35 for and kindred parts, and the faucet may then be applied to the gas container.

Another object of the invention is to improve generally the construction of the valves and the operating lever so that movement of the latter serves to actuate the 40 valves sequentially and in the most desirable manner to insure a prompt and steady discharge of liquid.

A further object is to mount the operating lever so that it will lie in a protected 45 position free from accidental operation, will occupy a relatively small space and will insure a maximum leverage to facilitate the operation of the valves.

Reference is now to be had to the accompanying drawings for a detailed description 50 of one embodiment of the present improvements, in which—

Figure 1 is a view in vertical section of a

siphon embodying the present invention and 55 having the gas container mounted directly on the liquid receptacle. Fig. 2 is a view taken on the plane indicated by the line 2—2 of Fig. 1 and looking in the direction of the arrows.

For convenience in illustration and description, the gas container *a* is shown herein as secured directly on the liquid receptacle *b* as by means of a split sleeve *c*, collar *c'* and bolts *d*. The form of the liquid 65 receptacle *b* and the gas container *a* is immaterial to the successful use of the present invention and it is to be understood that siphons of a different character from that herein illustrated may have the present improvements applied to them without departing from the scope of this invention. The bottom of the gas container *a* may be recessed, as at *a'*, to fit snugly over the neck 70 *b'* of the liquid receptacle *b* and may have 75 extending therethrough a gas passage *e* and a liquid discharge passage *f*, the lower ends of said passages being in communication with the interior of the liquid receptacle and the outer ends thereof being extended 80 through the wall of the gas container *a*, as at *e'* and *f'*. In the wall of the gas container *a* and in juxtaposition to the outer ends of the gas pipe *e* and the liquid discharge pipe *f* may be formed a duct *a''*. The 85 wall of the gas container *a* adjacent the outer ends of the passages *e* and *f* may be indented or recessed slightly, as at *a''*, to receive and position a plate *g* through which are formed ports *f'', a''* and *e''*, which are 90 adapted to register respectively with the free end *f'* of the liquid discharge pipe *f*, the port *a''* in the wall of the gas container *a*, and the free end *e'* of the gas pipe *e*. To this plate *g*, or rather to the wall of 95 the gas container *a*, may be secured the improved faucet *h* which is provided with ducts *f''*, *a''* and *e''*, which register respectively with the liquid discharge port *f''*, the gas port *a''* and the gas port *e''* in the plate 100 *g*, when the faucet *h* and the plate *g* are rigidly fastened to the wall of the gas container *a* as through suitable screws *i*. It will be evident that the intermediate plate *g* might be omitted but its use is desirable 105 since it facilitates the attachment of the faucet *h* to the container *a* and insures true registry of the several ducts. A suitable

packing, indicated at g' formed with corresponding ducts, may be interposed between the plate g and the faucet h .

It will be observed that the faucet h is formed as a single casting and is provided with a chamber h' with which communicate the gas ducts a^5 and e^8 . One wall of the chamber h' is formed by a movable diaphragm or valve k which normally closes the end of the gas duct a^5 so as to prevent the passage of gas from the gas container a through the gas port a^2 , duct a^5 , chamber h' , gas duct e^8 and gas passage e , into the liquid receptacle b . The diaphragm k is held to its seat on the end of the gas duct a^5 by a spiral spring l which seats at one end on a removable cap h^2 secured to the faucet h , and at the other end on the shoulder of a threaded plunger k' which rests on the diaphragm k . The outer or threaded end of the plunger k' passes loosely through an operating plate m and has threaded thereon a nut h^2 for the purpose of an adjustment which will hereinafter appear.

The discharge of liquid through the liquid discharge duct f^3 in the faucet h may be controlled substantially as heretofore by a flexible valve n normally held to its seat under the action of a spring o , which, in the present construction, for a purpose which will later appear, is of about the same strength as the spring l which controls the gas valve k , above described. The controlling spring o for the liquid discharge valve n is arranged within a removable cap h^3 secured to the faucet h , and abuts at its inner end against a shoulder on the valve stem n' , all as in the manner described with reference to the gas valve k . The free end of the stud n passes loosely through the operating plate m at one end, so that the plate m serves to connect operatively the valve stems n' and k' of the liquid valve and the gas valve respectively.

To the removable cap h^3 or to any other fixed part of the faucet h is secured a support p to which is pivotally attached, as at p' , the operating lever p^2 by which the positions of the valves k and n may be controlled. The lever p^2 carries thereon a stud p^3 which, when the lever is moved, engages the underside of the operating plate m and so actuates the valves. In carrying out the present invention it is desirable that the pivot pin p' of the lever p^2 should be disposed at one side of the vertical center line of the plate m so that the maximum initial leverage of the stud p^3 on the operating plate m will be secured when the operating lever is moved.

The arrangement above described permits the gas valve k to be opened prior to the opening of the liquid discharge valve n when the operating lever p^2 is moved, so that gas will be admitted into the liquid receptacle

prior to any movement of the liquid from the receptacle. The purpose of this is to insure the discharge of the liquid from the very moment of the opening of the liquid discharge valve under the action of fresh gas, whereby a full stream is obtained. Conversely, when the operating lever p^2 is returned to its original position the liquid discharge valve is permitted to close prior to the closing of the gas valve k so that a relatively small quantity of gas passes into the liquid receptacle and fills the space above the liquid. The provision of fresh gas prevents the liquid within the receptacle from becoming flat while the siphon remains idle.

While it is believed that the description of the parts thus far given indicates the nature of their operation it may be well to point out briefly the sequential movements when the operating lever p^2 is moved. By reason of the position of the stud p^3 with respect to the pivot pin p' and the center line of the plate m , the initial engagement of the stud with the underside of the plate serves to move the right hand end thereof (as viewed in Fig. 1) upward, about the left hand end thereof as a fulcrum. The plate m engages the adjusting nut h^2 on the stem k' of the gas valve k and unseats the valve, admitting fresh gas into the liquid receptacle b . Continued movement of the controlling lever p^2 and the stud p^3 serves to move the stud toward the left hand end of the plate n , as viewed in Fig. 1, and eventually to cause the plate to raise the stem n' of the liquid discharge valve n in the manner pointed out with respect to the gas valve k . Whereas the gas valve k is initially moved far from its seat, after the liquid begins to flow from the faucet h , the gas valve is permitted to move slightly toward its seat so that the discharge of the liquid continues under a uniform pressure. The extent of the opening of the gas valve k when the lever p^2 is thrown to the open position, may be regulated by the adjusting nut h^2 , as will be understood. When the lever p^2 is in its open position it will be observed that the stud p^3 stands in the same vertical plane with the pivot pin p' of the lever, so that the latter is held in its open position automatically and the flow of liquid permitted for any desired time, without the especial attention of an attendant.

Another feature of importance which should be noted here is the fact that the improved faucet and the disposition of the valves permits the operating lever p^2 to lie relatively close to the gas container a so that the space taken up by the siphon is not increased, as is usual, by the projecting of the operating lever. For instance if the siphon is to be incased for shipping,

the size of the receptacle need not be increased by reason of the disposition of the operating lever. Then too, the improved operating lever may not be operated easily by mistake or by inadvertent contact with other objects, as so often happens with siphons now in general use. The form of operating lever employed permits it to be extended for a considerable distance beyond the stud p^3 so that the effective leverage employed in operating the plate m is materially increased and the degree of opening of the valves may accordingly be controlled to a nicety.

It will be seen that in the construction illustrated there is provided with the usual liquid pipe a^6 which is carried by the gas container a and extends downwardly into the liquid receptacle b , a telescoping section a^7 mounted slidably on its lower end. This section a^7 may carry a gasket a^8 of rubber or other suitable material, held in place normally by a removable screw threaded bushing a^9 . The gasket a^8 embraces snugly the liquid tube a^6 and permits a sliding engagement of the telescoping section a^7 with the liquid tube. The extreme lower end of the telescoping section a^7 may be provided with points a^{10} , which, when the tubes are in their normal position, rest on the bottom of the liquid receptacle b and permit a free and constant flow of liquid into the tubes.

We claim as our invention:

1. The combination of a liquid receptacle, a gas container in communication therewith, a faucet through which the liquid is discharged, a valve carried by the faucet to control the discharge of liquid, an independent valve carried by the faucet to control the passage of gas from the gas container to the receptacle, valve stems for said valves, an operating plate loosely and operatively disposed between said valve stems so as to permit relative movement of the valves and an operating lever mounted on the faucet in operative relation to said plate, whereby upon movement of the lever the valves are moved.
2. The combination of a liquid receptacle, a gas container in communication therewith, a faucet through which the liquid is discharged, a valve carried by the faucet to control the discharge of liquid, an independent valve carried by the faucet to control the passage of gas from the gas container to the receptacle, valve stems for said valves, an operating plate through which

stems extend loosely whereby relative movement of the valves is permitted, and an operating lever mounted on the faucet and operatively disposed with respect to the latter to open the gas valve prior to the opening of the liquid valve, continued movement of the lever serving to open both of said valves.

3. The combination of a liquid receptacle, a gas container in communication therewith, a faucet through which the liquid is discharged, a valve carried by the faucet to control the discharge of liquid, an independent valve carried by the faucet to control the passage of gas from the gas container to the receptacle, valve stems for said valves, an operating plate through which said valve stems extend loosely whereby relative movement of the valves is permitted, an operating lever mounted on the faucet and operatively disposed with respect to the latter to open the gas valve prior to the opening of the liquid valve, continued movement of the lever serving to open both of said valves, and independent springs to seat said valves respectively when the lever is returned to its original position, the plate permitting the liquid valve to close before the closing of the gas valve.

4. The combination of a liquid receptacle, a gas container in communication therewith, a faucet through which the liquid is discharged, a valve carried by the faucet to control the discharge of liquid, an independent valve carried by the faucet to control the passage of gas from the gas container to the receptacle, valve stems for said valves, an operating plate through which said valve stems extend loosely, an operating lever mounted on the faucet and a stud carried on the lever to engage the underside of the plate and tilt the same when the lever is moved, whereby the gas valve is opened prior to the opening of the liquid valve, continued movement of the stud serving to open both of said valves, said stud being positioned on the lever to lie directly over the pivot pin thereof when the lever is thrown to the open position whereby the latter is held in the last named position automatically.

This specification signed and witnessed this twenty-fourth day of May A. D., 1913.
